UNITED STATES PATENT OFFICE.

ROBERT CLARKSON, OF EAST ST. LOUIS, ILLINOIS.

CAN OPENER.

Application filed March 12, 1924. Serial No. 698,690.

To all whom it may concern:

Be it known that I, ROBERT CLARKSON, a citizen of the United States, residing at East St. Louis, in the county of St. Clair 5 and State of Illinois, have invented certain new and useful Improvements in Can Openers, of which the following is a specification.

This invention relates to can openers and 10 has for its object the provision of a simple and inexpensive device especially adapted for household use whereby metal cans or containers may be easily and quickly opened without exposing the user of the device to 15 the risk of injury through contact by the fingers with the jagged edges of the opening in the container. The invention seeks to provide a device which may be readily secured in working position upon a kitchen 20 table or other fixed support and manipulated to first partly sever the top of the can from the body thereof and then lift the partly severed portion to permit the contents of the can to be discharged. Another 25 object of the invention is to provide a can opener of such form that, when in use, it will tend to hold the can in position upon the table so that slipping or undue rotation of the can will be prevented. Other objects 30 will appear incidentally in the course of the following description.

One embodiment of my invention is illustrated in the accompanying drawing, in which—

35 Figure 1 is a plan view of my improved can opener, showing the manner in which it is brought to bear upon a can when in use, and

40 Fig. 2 is a side elevation of the same, with a can indicated in dotted lines.

In carrying out my invention, I employ a platform consisting of a base or lower jaw 1 which is adapted to engage against the under side of a table top, indicated at 2, and 45 a post or standard 3 rising from the outer edge of said jaw and equipped at its upper end with an offset 4 having an internally threaded bore to receive a clamping screw 5 which is engaged therethrough to bear 50 upon the upper side of the table top or other support, as shown clearly in Fig. 2. It will be readily understood that, by turning the screw home against the table top, the device will be firmly clamped in place. 55 Through the jaw 1 adjacent one end thereof is formed an opening to receive a pin or

stud 6 formed at the lower end of a rocking standard 7 and around this pin or stud is fitted a coiled spring 8 bearing at one end against the side of the jaw 1 and at its opposite end against a cotter pin or similar retainer 9 carried by the pin or stud. The said spring serves to hold the rocking standard 7 against the side of the jaw and the edge of the fixed support with sufficient friction to maintain the standard in any position in which it may be set while at the same time permitting it to rock to the extent necessary for a successful operation of the device. At the upper end of the standard 7 is an eye 10 adapted to receive a pin or stud 11 formed on the side of an offset longitudinal extension 12 of the lever or handle 13. The extension 12 is connected with the end of the main body of the handle or 70 lever 13 by a cross bar or bridging portion 14 which is formed integral with the handle and the extension, and to the side of the handle immediately at the said cross bar is secured a blade 15 which has its upper end 75 bearing against the under side of a reinforcing rib 16 formed on the side of the handle. The lower end of the blade is tapered downwardly to an approximately central point 17 and the tapered or converging edges are 80 beveled so as to serve as cutters. The extension 12 is reduced beyond the pivot pin or stud 11 to terminate in a flat blade-like member 18, the purpose of which will presently appear.

In using the device, the anchoring clamp is secured upon the fixed support, as shown and described, and the rocking standard 7 is swung upwardly so as to project above the table top. The pin or stud 11 carried 95 by the handle is engaged laterally through the eye 10 so that the handle may be oscillated or rocked pivotally about the said eye as a center. The can to be opened, indicated at 19, is placed upon the table top so that it will project under the blade 15 with the side of the can clearing the standard 7, as shown clearly in Fig. 1. A downward pressure is then exerted upon the lever or handle 13 so that the point of the blade 100 15 will be caused to pierce and pass through the top of the can, making a cut such as is shown at 20. The blade is then lifted, the can partially rotated and a second cut, indicated at 21, is formed in the same manner, the second cut overlapping the end of the first cut, as indicated at 22. This proc-

ess is repeated until the overlapped cuts or incisions extend almost around the entire top of the can. The handle member is then disengaged from the standard and the flat blade or tooth 18 is engaged under the severed edge of the top so that the said top may be pried upward without any necessity of the operator grasping the same, and injury to the fingers is thereby avoided. 5
10 By properly twisting or rocking the pry 18 beneath the edge of the partly severed top, the top may be raised sufficiently to permit the entire contents of the can to be withdrawn. When the blade carrying 15 handle is disengaged from the standard, the standard may be lowered to a substantially horizontal position extending alongside the edge of the table or other fixed support so that it will be out of the way 20 during subsequent handling of the can and may be easily brought into operative position if a second can is to be opened immediately or within a short time. If the can opener will probably not be needed for 25 some appreciable period of time, the clamping screw may be released so that the entire device may be set aside.

It will be readily noted from the foregoing description, taken in connection with 30 the accompanying drawing, that I have provided an exceedingly simple and inexpensive device which will be found highly efficient in operation. When pressure is applied through the handle to force the blade 35 into and through the top of the can, the pressure is exerted in both directions from the central line of the blade so that, while the top of the can is cut through, the exerted pressure serves to hold the can against 40 movement instead of tending to push it out of the path of the knife. The offset construction of the working end of the handle permits it to readily clear the side of the can, and the flat tapered pry 18 is an ad-

vantageous adjunct to the opener inasmuch 45 as it permits the partly severed can top to be raised without any necessity for the fingers of the operator to grasp the same, and injury to the fingers which are now frequently caused by contact with the rough 50 jagged edges of the cut portions is avoided. The rocking standard permits the device to be adjusted back and forth relative to the table so that it may be quickly brought into proper operative relation to cans of 55 various heights or diameters and the connection or mounting of the handle upon the standard is such that the handle or lever will be firmly supported but may be easily disengaged therefrom when the device is 60 not to be immediately used. Moreover, the offset construction of the handle member, while providing clearance for the can, also brings the greater portion of the handle into the same plane as the standard so that, 65 if the handle should be thrown quickly or carelessly rearward with respect to the can, it will be caused to impinge against the far or rear side of the standard and will be thereby supported in such a position that 70 it may be easily grasped when its use is again desired or necessary.

Having thus described the invention, I claim:

A can opener comprising a standard, a 75 handle member having a laterally offset end portion extending parallel with its greater length, a pin projecting from the side of the offset portion of the handle member adjacent the free end thereof to 80 pivotally engage the standard, a blade secured rigidly to the side of the handle member at the base of the offset portion thereof, and a reduced flat-sided pry extending from the extremity of the offset portion. 85

In testimony whereof I affix my signature.

ROBERT CLARKSON. [I. S.]
